UNITED STATES PATENT OFFICE.

MICHAEL McCARTHY, OF MIDDLETOWN, CONNECTICUT.

FLOATING ANCHOR AND OILER.

SPECIFICATION forming part of Letters Patent No. 378,171, dated February 21, 1888.

Application filed October 13, 1887. Serial No. 252,216. (No model.)

To all whom it may concern:

Be it known that I, MICHAEL McCARTHY, of Middletown, Connecticut, have invented a new and useful Nautical Apparatus, which I 5 denominate a "Floating Anchor and Oiler," of which the following description and claims constitute the specification, and which is illustrated by the accompanying sheet of drawings.

This invention consists of a flat bag, made of 10 canvas or other porous material and provided with rigid edges, and adapted to hold oil and to be held in the water at some distance from the deck of a ship by means of a rope extending from the apparatus at substantially right 15 angles to the surface thereof to the vessel.

The function of the apparatus consists in holding the bow of the vessel to windward when outriding a storm, and consists, also, in casting oil upon the waters some distance to windward 20 of the vessel to which it is attached.

Figure 1 of the drawings is a perspective view of the apparatus. Fig. 2 is a fragmentary front view of the left-hand upper portion of the same. Fig. 3 is a vertical section on 25 the vertical dotted line of Fig. 2.

A is the frame of the apparatus, made, preferably, by uniting four iron pipes of equal length, and provided with right and left hand screw-threads, respectively, upon the opposite 30 ends of each, with four hollow elbows, the interiors of which are furnished with corresponding screw-threads, and the exteriors of which are provided with eyes or staples, to which the ropes B are respectively attached. Those 35 ropes are of equal length, and their outer ends are made fast to the ring C. The rope D extends from that ring to the deck of the ship when the apparatus is in the water, and the rope E extends from one corner of the apparatus to the deck of the ship for a supplementary purpose hereinafter mentioned.

The bag F is composed of two thicknesses of heavy canvas, and is preferably bound with the cord G, while the two thicknesses are fastened 45 together by the grommets H, of which any suitable number may be used to accomplish the desirable object of holding the two thicknesses of the bag together at sundry points upon their surfaces. The grommets I are also fastened 50 through the bag F, near its border, on all sides thereof, and the riveted rings J have their

heads united through those grommets, while their outer parts encircle the tubes which compose the four sides of the frame A. The bushing K, provided on its inner end with the tube 55 L, and capable of being closed at its outer end by the screw-cap M, gives entrance for oil to the interior of the bag F. A supplementary bag, N, may be filled with air or oil and attached to the upper side of the frame A by means of 60 grommets and rings in substantially the same way that the bag F is held within the frame A.

When out of use, the frame may be taken apart by unscrewing its pipes from its elbows, and the bags may be emptied and folded up 65 with the parts of the frame, so as to occupy a small space on shipboard.

When the apparatus is to be used, the bag F is filled with linseed or other animal or vegetable oil, and the bag N is filled with oil or 70 other like liquid or inflated with air, and then the two bags and the frame are assembled in the relative position shown in Fig. 1.

The mode of operation is as follows: When the vessel is hove to with its head to the wind 75 to outride a storm, the frame and the bags attached thereto are cast overboard at or near the bow of the vessel. The rope D is retained on board, and the bag N floats upon the top of the water, while the frame A and the bag F are 80 submerged in such a position that the plane of the frame is at right angles to the direction of the rope D. As the wind drives the vessel to leeward, the rope D is made taut, and the apparatus, not being materially affected by the wind, 85 is not driven with the vessel, but remains at whatever distance off the bow the length of the rope D will permit. While the apparatus remains in that position it powerfully resists the leeward motion of the vessel, and thus acts like 90 an anchor in the water. At the same time oil exudes through the meshes and pores of the bag F and rises thence to the surface of the water, where it powerfully tends to allay the 95 waves. In serving like an anchor, the apparatus operates to keep the vessel out of the trough of the sea, and in serving as a distributor of oil some distance off the bow of the vessel the apparatus operates to diminish the violence of the advancing waves before they 100 reach the bow of the ship. When the apparatus is no longer needed overboard, the rope

D is slackened and the rope E is pulled, and the apparatus is thus brought to a horizontal position upon the surface of the water, whence it is easily hauled on board.

5 The bag N may be omitted and the position of the apparatus near the surface of the water be maintained by its own buoyancy. So, also, the bag F may be lashed to the frame with ropes, instead of being held thereon by rings, and the 10 grommets which hold the two thicknesses of the bag F together may be omitted, though I prefer to use those grommets and those rings.

The size of the apparatus should be adapted to the size of the vessel to which it is to be attached, and I calculate that one having sixteen 15 square feet of surface on each side is large enough for a vessel of a hundred tons, and that apparatus of correspondingly larger sizes will hold correspondingly larger vessels out of the 20 trough of the sea.

I claim as my invention—

1. A floating anchor and oiler consisting of a flat bag, made of canvas or other porous material and provided with rigid edges and adapted

to hold oil, and to be held in the water at some 25 distance from the deck of a ship by means of a rope extending from the apparatus at substantially right angles to the surface thereof to the vessel, all substantially as described.

2. The combination of a rigid frame and a 30 flat bag, made of canvas or its equivalent and adapted to hold oil, and removably fastened within the frame, so as to operate therewith and be detachable therefrom, all substantially as described.

3. The combination of the frame A, consisting of pipes and elbows united by right and left hand screw-threads, with the flat bag F, made of canvas or other porous material and adapted to hold oil, and held within the frame 40 by the rings J, or their equivalents, all substantially as described.

October 12, 1887.

MICHAEL McCARTHY.
